(57) **CLAIM**

The ornamental design for a heat dissipating device for batteries or electric devices, as shown and described.

DESCRIPTION

1. Heat dissipating device for batteries or electric devices

1.1 : Front

1.2 : Back

1.3 : Left

1.4 : Right

1.5 : Top

1.6 : Bottom

1.7 : Perspective

1.8 is an enlarged partial perspective view; and

1.9 is a perspective view, shown in an environment.

Fig. 1.8 is a partially enlarged view taken along the A-A' line shown in the fig 1.7; fig. 1.9 is a reference view showing the state of use in which the article according to the present design is used by being sandwiched between a plurality of battery cells and a case.
